UNITED STATES PATENT OFFICE.

WILLIAM H. LIEBER, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

TRIMMER-SAW.

1,128,795.

Specification of Letters Patent. Patented Feb. 16, 1915.

Application filed May 23, 1914. Serial No. 840,935.

To all whom it may concern:

Be it known that I, WILLIAM H. LIEBER, a citizen of the United States, residing at Milwaukee, in the county of Milwaukee and 5 State of Wisconsin, have invented a certain new and useful Improvement in Trimmer-Saws, of which the following is a specification.

This invention relates to improvements in 10 the construction of saw mill machinery and particularly to improvements in apparatus for permitting control of the positions of a plurality of trimmer saws or similar devices, from a common operator's stand.

15 An object of the invention is to provide a device for permitting either independent, selective or collective positioning of a plurality of trimmer saws, which is simple in construction and efficient in operation.

20 Some of the more specific objects of the invention are as follows:

To provide a device for permitting either individual, selective or collective actuation of a plurality of saws irrespective of the 25 positions of prior setting of the individual saws at the time such actuation is desired.

To provide means for permitting successive positioning of any predetermined allotment of the saws, as distinguished from the 30 simultaneous positioning which has been customary in devices of the prior art.

To provide means for permitting rapid successive collective positioning of all of the saws.

35 To provide means for permitting rapid successive selective positioning of the saws.

To provide means for automatically returning the collective and selective actuating mechanism to normal or mid position.

40 To provide means in the fluid pressure actuated saw actuating device, for insuring a proper supply of operating fluid to each of the saw actuating devices during collective or selective actuation thereof. This feature is accomplished through the successive 45 rather than the simultaneous actuation of the saws and with the use of a common header for supplying all of the saw actuating devices.

50 To provide means for preventing the saws which are out of cutting position from moving into cutting position upon failure of the fluid pressure supply.

To provide a device in which the collective 55 and selective controlling actuating de-

vices are operable with a minimum expenditure of manual power. This result is accomplished by the use of a manually controlled motor which may be operated either mechanically, pneumatically or electrically 60 as desired. In the present disclosure the motor consists of a pneumatically operated piston, but any of the well known mechanical devices for accomplishing a similar result may be substituted without departing 65 from the scope of the present invention.

To provide a fluid pressure admission means or valve for each of the saw positioning devices, which is simple in construction and efficient in operation. In the present 70 disclosure the fluid admission valves are subjected to an unbalanced pressure which tends at all times to maintain the valves in a position corresponding to saws up position, so that upon release of the individual controlling levers, the valves automatically tend 75 to return the levers to saws up position.

To provide means for permitting the use of but a single connector between each of the individual controlling levers and its corresponding saw position controlling valve. The connector involved in the present invention is so constructed as to permit efficient use thereof in conjunction with guiding pulleys of very small diameter, this feature being the result of the formation of the 80 portion of the connector adjacent to the guiding pulley of highly flexible material.

Some of the novel features shown and described herein are claimed in co-pending application Serial No. 749,539, filed February 17, 1913.

A clear conception of an embodiment of the invention may be had by referring to the drawings accompanying and forming a part 95 of this specification in which like reference characters designate the same or similar parts in the various views.

Figure 1 is an end view, partly in section, of a trimmer saw position controlling actuating device showing the master lever in mid position and showing some of the individual levers in each of the extreme positions. Fig. 2 is a fragmentary front view of a trimmer saw position controlling actuating device. Fig. 3 is a fragmentary plan view of a trimmer saw position controlling actuating device, the actuating levers and supporting shaft therefor being omitted. Fig. 4 is an end view, partly in section, of 100 105 110

a trimmer saw position controlling actuating device showing the master lever and the motor controlled thereby, in collective controlling position, and showing all of the individual levers in saws up position. Fig. 5 is a front view of the master or collective actuating rod. Fig. 6 is a front view of the intermediate lever actuating rod. Fig. 7 is a front view of the selective or slasher lever actuating rod. Fig. 8 is an end elevation, partly in section, showing the general arrangement of a trimmer saw equivalent and the saw positioning mechanism therefor. Fig. 9 is a transverse vertical section through one of the individual saw positioning mechanisms. Fig. 10 is a fragmentary transverse vertical section through one of the individual saw positions controlling valves and a portion of the connection leading to the individual actuating device thereof.

In the device disclosed in the drawings the saws are brought into cutting position by their own weight combined with that of saw supporting arms and the elements bearing against these arms, and are raised out of cutting position by means of fluid pressure admitted below the pistons of the saw positioning mechanisms. In order to facilitate explanation, the positions corresponding to into and out of cutting positions will be designated as "saws down" and "saws up" position, respectively. It should be understood, however, that these terms are correct only when applied to an overhead trimmer, and it is not intended to limit the application of this invention to that type of trimmer by the use of these terms. The term "collective" as used in the present specification designates all of the saws controllable by the mechanism. The term "selective" designates a predetermined allotment or portion of the total number of saws commonly known as the slasher saws. The saws other than the selective saws are designated as "intermediate" saws. The collective saws therefore include both the selective or slasher saws and the intermediate or non-slasher saws.

The ordinary trimmer saw equipment includes a lumber conveying table 73, upon which the material to be trimmed is automatically fed toward the saws 67 by means of a suitable conveying mechanism, see Fig. 8. The individual saws 67 are supported by arms 66 which swing about stationary pivots 69 on the mill framing. A common driving shaft 70 carries a series of driving pulleys 71 which are drivingly connected to the saw pulleys 72 by means of suitable belts 68. The location of the pivots 69 of the arms 66 is such that with the saws 67 in saws down position, the belts 68 are taut, and with the saws 67 in saws up position, the belts 68 are flexed.

65 Each of the individual saw positioning

means consists of a cylinder 62 having an upper end head 81 by means of which the cylinder is fixed to the beam 61 above the saws 67. The lower end of the cylinder 62 is provided with a flange 82 to which is secured a combined lower end head and bracket 63. The cylinder 62 is preferably formed of piping having threaded ends for connection with the end head 81 and flange 82, see Figs. 8 and 9.

A piston 84 is reciprocable within each of the cylinders 62 and is capable of imparting motion to its respective saw 67 through a piston rod 64, connection 96, adjustable connection 65 and arm 66. The point of exit of the piston rod 64 from within the cylinder 62 is packed by means of a suitable stuffing box 87. The combined weight of the piston 84, rod 64, connections 96, 65, saw carrying arm 66, and saw 67, is capable of moving the saw 67 rapidly into saws down or cutting position upon release of fluid pressure from within the lower piston chamber. The upper portion of the cylinder 62 is provided with a relief port 83 located a short distance below the end of the cylinder, which permits escape of the major portion of the air from within the cylinder 62 as the piston 84 travels upwardly therein but which permits retention of sufficient air within the cylinder to form an air cushion for the piston at the end of its up stroke.

The bracket 63 has a valve casing 77 formed in the lower end thereof. The valve casing 77 is bored to receive the piston valve 95, the lower end of which is of enlarged diameter as compared to the upper portions thereof. The valve 95, see Fig. 10, is formed with two cylindrical portions 100, 101 of equal diameter, which are connected by means of a valve stem 102. The lower valve portion 100 controls communication between the fluid pressure inlet pipe 93 and the common inlet and exhaust port 92. The upper valve portion 101 controls communication between the port 92 and the exhaust port 94. The common inlet and exhaust port 92 passes upwardly through the bracket 63 and opens directly into the lower piston chamber of the cylinder 62. The upper end of the port 92 is provided with a ball check valve 89 which permits the passage of fluid through the port 92 into the cylinder 62 but prevents return of fluid to the port 92. A by-pass port 90 connects the port 92 with the cylinder 62 at a point somewhat above the lower end of the cylinder. The port 90 provides a cushion for the piston 84 in its downward travel, by retaining some of the fluid within the lower piston chamber and permitting the piston 84 to compress this retained fluid during its travel beyond the end of the port 90.

The common fluid pressure supply pipe or header 76 is connected with the valve cas-

ings 77 through the branch pipes 93. Each branch pipe 93 connects with the bore of its corresponding valve casing at a point somewhat above the enlarged lower end of the 5 valve 95, thus maintaining the annular upper surface of the valve 95, which is formed above and directly adjacent to the enlargement of the lower end of the valve, under unbalanced pressure. The unbalanced pressure 10 upon the valve 95 tends to force the valve in a downward direction and to maintain fluid pressure beneath the saw positioning piston 84 at all times.

The valves 95 have their upper ends connected to suitable actuating connections or wires 75 by means of short lengths of highly flexible material such as cables or chains 86. These chains 86 coact with small guide pulleys 85 carried by brackets 98. The 20 brackets 98 are swingable about the axes of the valves 95 by loosening the bracket retaining cap screws 99 which are preferably located substantially concentric with the valve axes. With this construction the 25 brackets 98 may be shifted to permit actuation of the valves 95 from any angular direction with equal efficiency. The upper ends of the valves 95 are adapted to coact with projections formed on the safety devices or stops 88 and to carry these projections in contact with the bracket stops 91. The safety stops 88 become effective whenever the fluid pressure in the lower piston chambers of the cylinders 62 fails, to prevent 35 the saws 67 from moving downwardly at such times. This safety device, however, does not form any part of the present invention and further description thereof is therefore deemed unnecessary.

40 The operating ends of the wires or connectors 75 are connected to the bell cranks 74 through suitable adjusting devices 78, by means of which the proper tension upon the connectors 75 may be retained. The bell 45 cranks 74 are pivoted in swivel brackets 79 which are pivoted in stationary brackets 80 by means of pivot pins 97. The remaining arms of the bell cranks 74 are connected to the lower ends of the operating wires or 50 connectors 50, the upper ends of which are connected to the individual operating levers as will be later explained. The axes of the connectors 50 and the pins 97 coincide so that the swivel brackets 79 may be swung 55 into any desired angular position for proper actuation of their corresponding valves 95.

The saw controlling valve actuating device comprises a plurality of individual levers 15, 16, and a master lever 17, all of 60 which are mounted to swing about a common supporting shaft 21, see Figs. 1 to 4. The levers 15, 16, are alike in construction and have front and rear projections 42, 43, extending radially from their supporting 65 hubs. The rear projections 43 are provided

with openings for connecting the operating connectors 50 to the levers. The upper extremities of the levers 15, 16, are formed to permit ready manipulation of the levers by means of the finger tips, and are provided 70 with saw designating numerals. The levers 15 which are provided with the odd numbered saw designating numerals at the upper ends thereof, are adapted to actuate the selective or slasher saws. The levers 16 75 which are provided with the even numbered saw designating numerals, are adapted to actuate the intermediate or non-slasher saws. The arrangement of levers as herein shown and described applies to a fourteen 80 saw trimmer in which the slasher and intermediate saws are alternately arranged, but it should be understood that this disclosure is merely illustrative of one form of the invention and that modifications in the 85 number of saws and in the arrangement of the individual levers and saws might be made without departing from the present invention. The lever supporting shaft 21 is mounted in bearings 19, 20, of which, for 90 purposes of description, the bearing 19 will be designated as the front bearing, while the bearing 20 will be designated as the rear bearing. The bearings 19, 20, are supported upon a suitable lever bracket 18 which is 95 supported upon the supporting beam 23 mounted adjacent to the operator's stand. The collar 38 serves to prevent the master lever 17 from leaving the overhanging end of the shaft 21.

100 The master lever 17 differs from the individual levers 15, 16, in that it has no projections 42, 43, but has a downwardly extending valve operating projection 24. The lower extremity of the projection 24 coacts 105 with a recess in the upper portion of the slide valve 25. The slide valve 25 is adapted to control the admission and exhaust of fluid under pressure to the piston chambers of the motor cylinder 22, see Figs. 1 and 4. 110 In practice it would be preferable to subject the upper portion of the valve 25 to fluid pressure, but the disclosure has been omitted to simplify explanation and disclosure of the invention. The ports 35 normally connect the extreme ends of the cylinder 22 with the atmosphere. The pressure admission port 26 normally communicates with the central recess in the lower portion of the slide valve 25. The master 115 lever 17 is normally maintained in its vertical or mid position by means of a coiled spring 41 the ends of which cross each other and coact with opposite sides of the stationary projection 40 on the front bearing 19 and with the master lever returning pin 39 which projects laterally from the master lever. The spring 41 besides tending to return the master lever 17 to mid-position, also returns the valve 25 120 125 130

to mid position upon release of the master lever, and automatically establishes communication between the chambers on the opposite sides of the motor piston 34 and the atmosphere.

The motor piston 34 is provided with a rod 33 which projects through both end heads of the cylinder 22. The ends of the rod 33 coact with the lower master and slasher bell crank arms 27, 28, respectively, which are secured to the vertical shafts 31, 32, respectively. The shaft 31 is mounted in bearings in the bracket 29, while the shaft 32 is mounted in bearings in the bracket 30, these brackets being supported directly from the sides of the beam 23. The upper bell crank arms 48, 49, are secured to the upper ends of the shafts 31, 32, respectively, and are disposed substantially at right angles to the lower bell crank arms 27, 28, respectively. Each of the shafts 31, 32, is provided with a returning arm 36 which has a portion extending parallel to the axis of its corresponding shaft. The bell crank returning springs 37 have crossed ends which coact with opposite sides of the arms 36 and adjacent webs on the bearings 29, 30, respectively, and tend to maintain the bell cranks in the position indicated in Figs. 1 and 3. With the arms 27, 28, in normal position, the piston 34 is maintained in mid position through the rod 33, so that the springs 37 automatically return the piston 34 to mid position upon return of the valve 25 to mid position.

The lever bracket 18 is provided with two parallel longitudinally extending slots in the front portion thereof, and one longitudinally extending slot in the rear portion thereof. These slots are located underneath the projections 42, 43, of the levers 15, 16. The master rod 44, see Figs. 1 to 5, is normally slidably mounted within one of the slots in the front portion of the bracket 18 and has its end connected to the swinging extremity of the bell crank arm 48. The intermediate lever actuating rod 45, see Fig. 6, is normally slidably mounted in the remaining slot in the front portion of the bracket 18, and has its one end connected to one extremity of a cross connecting lever 47 which is pivotally mounted upon the bracket 18 by means of a pivot 52. The slasher lever actuating rod 46, see Fig. 7, is normally slidably mounted in the slot in the rear portion of the bracket 18, and has one of its ends connected to the swinging end of the bell crank arm 49, and has its opposite end connected to the remaining extremity of the 60 cross connecting lever 47.

The master rod 44, see Fig. 5, is provided with a series of serrations or notches, the side walls 56 of which are normally adjacent to the corresponding projections 42 of the individual levers 15, 16. The inclined lever

releasing surfaces 53 of the master rod 44 are so located that no two of the notches in the master rod 44 are of the same width. The intermediate lever actuating rod 45 is provided with a series of serrations or 70 notches, the side walls 57 of which are normally adjacent to the corresponding projections 42 of the intermediate levers 16. The inclined intermediate lever releasing surfaces 54 of the rod 45 are so located that 75 no two of the notches in the intermediate lever actuating rod 45 are of the same width. The slasher lever actuating rod 46 is provided with a series of serrations or notches, the side walls 58 of which are normally adjacent to the corresponding projections 43 of the slasher levers 15. The inclined slasher lever actuating surfaces 55 of the slasher lever actuating rod are so located that no two of the notches in the rod 85 46 are of equal width.

The levers 15, 16, are normally held in a position corresponding to saws up position by means of the unbalanced pressure upon the valves 95. If, however, these levers are 90 placed in positions corresponding to saws down position, the levers are retained in such position by means of leaf springs 51 which are secured to the bracket 18 and which have wedge shaped ends coacting in 95 central grooves in the lower portions of the hubs of the levers 15, 16.

During the normal operation of the device, and at such times when the collective and selective positioning of the saws 67 is 100 not desired, the master lever and the mechanism controlled thereby is in the position shown in Figs. 1 and 3, the actuation of the individual levers 15, 16, being unrestrained. With the mechanism thus positioned, any one or more of the individual saws 67 may 105 be brought into cutting or saws down position by manually pulling the corresponding lever 15, 16, toward the operator. A pull on one of the levers 15, 16, acts through the corresponding connector 50, bell crank 74, connector 75 and chain 86 to raise the valve 95, thus establishing communication between the chamber of the corresponding saw actuating piston 84 and the atmosphere 110 through the ports 90, 92 and 94. This release of fluid pressure from beneath the piston 84 permits the saw 67 controlled thereby to move into cutting position due to the action of gravity upon the saw and the connected elements. During the upward movement of the valve 95, the safety device or stop 88 is released so that the piston rod 64 is free to move downwardly. As the piston 84 passes the port 90 a small amount of fluid is confined in the space at the lower end of the cylinder 62. The continued downward movement of the piston 84 compresses the confined fluid and forms an 115 automatic cushion for the saw 67 at the end 120 125 130

of its downward stroke. When the lever 15, 16, has been pulled forward to its extreme position, the wedge of the corresponding leaf spring 51 adjacent to the hub of the 5 lever snaps into the recess in the lower portion of the hub and holds or locks the lever in saws down position. Upon release of the lock afforded by the spring 51, the fluid pressure from the supply header 76 acting upon the unbalanced area of the valve 95, 10 automatically forces the valve 95 downwardly and causes the corresponding individual lever to assume its extreme position toward the right as viewed in Fig. 1, which 15 position corresponds of saws up position. As the valve 95 assumes its lower position as disclosed in Figs. 9 and 10, the communication to the atmosphere through the port 94 is cut off and fluid under pressure is admitted from the common supply header 76 20 through the pipe 93 and ports 90, 92, to the lower piston chamber of the cylinder 62, past the ball valve 89. This admission of the fluid to the chamber below the piston 84 immediately causes the piston and the saw 25 controlled thereby to rise, thus placing the saw out of cutting position. As the piston 84 travels upwardly it cuts off communication from the interior of the cylinder 62 30 to the atmosphere through the port 83, thus confining a small amount of air in the chamber above the port 83. The continued upward movement of the piston 84 compresses this confined air and forms an automatic 35 cushion for the piston 84 at the end of its up-stroke. During the upward movement of the piston rod 64, the safety stop 88 will not clutch the rod 64, such clutching occurring only during the downward movement 40 of the rod 64 and with the valve 95 in its lowermost position.

It will be noted that the saws 67 are placed into cutting position by a positive pull on their corresponding individual levers 15, 16, but may be placed out of cutting position automatically by merely releasing the lock afforded by the springs 51 upon the corresponding individual levers. It should also be noted that if for any reason 50 the pressure in the supply header 76 fails with the valves 95 in their lowermost position, the safety device or stop 88 will automatically prevent dropping of the corresponding saws below the positions held by 55 these saws at the time of the fluid pressure failure.

If it is desired to operate the saws collectively to raise the same, this may be done by pulling or swinging the master lever 17 toward the operator. Such motion of the master lever 17 causes the valve 25 to establish communication between the pressure inlet port 26 and the port 35 at the right of the cylinder 22 as viewed in Fig. 1. This 60 establishment of communication permits

fluid under pressure to enter the right hand piston chamber and to force the piston 34 toward the left to the extreme position shown in Fig. 4. During movement of the piston 34 to its extreme left position as 70 shown, the rod 33 forces the bell crank lever 27, 48, to swing in a clockwise direction as viewed in Fig. 3 and causes the master rod 44 to move toward the right. Movement of the master rod 44 toward the 75 right, causes the inclined surfaces 53 thereof to successively coat with the adjacent projections 42 on the individual levers and to swing these levers a sufficient amount to release the lock afforded by the corresponding springs 51. This release of the individual levers immediately permits the unbalanced pressure on the corresponding valves 95 to become effective and to successively place all of the valves 95 of the corresponding individual levers into saws up position with a resulting movement of the saws out of cutting position. If previously to the master actuation, any of the saws 80 have been in saws up position, such saws and their corresponding actuating mechanism will not be affected by the movement of the master rod 44. It should be noted that by forming the detents in the upper portion of the master rod 44 of different 85 widths, the saws are successively actuated, thus permitting a gradual flow of the fluid under pressure from the common header 76 to the actuating cylinders. This feature is of importance since it permits the proper 90 supply of actuating fluid to each of the saw actuating cylinders 62 at the proper time, whereas if the actuation of the saws is simultaneous, the header 76 must either be made very large in diameter or the saws 95 near the end of the header remote from the supply inlet will not receive a proper supply of actuating fluid. While the actuation 100 of the saws in the present device is successive, the total time consumed in raising all 105 of the saws in the usual trimmer saw equipment of from ten to twenty saws, would not be objectionable and the advantage of having a proper supply of actuating fluid for each of the saws would be a decided one. 110 Upon release of the master actuating lever 17 by the operator, the spring 41 immediately becomes effective in returning the master lever 17 to its normal or mid position. This return of the master lever 17 115 causes the valve 25 to assume its mid position and to establish communication between the chamber at the right of the motor piston 34 and the atmosphere through the port 35. Upon release of this pressure the piston 34, through the rod 33, is returned to 120 mid position by the spring 37 which presses against the returning arm 36 and the web of the bracket 29, causing the bell crank 27, 48, to assume its normal position as shown 125 130

in Fig. 3. With the return of the bell crank arm 48 to normal position, the normal position of the master rod 44 is restored.

If it is desired to operate the saws 67 selectively to lower the slasher saws and to raise the intermediate saws, this may be done by pushing or swinging the master lever 17 away from the operator's stand. Such motion of the master lever 17 causes the valve 25 to establish communication between the pressure inlet port 26 and the port 35 at the left of the cylinder 22 as viewed in Fig. 1. This establishment of communication permits fluid under pressure to enter the left hand piston chamber and to force the piston 34 toward the right. As the piston 34 moves toward the right, the rod 33 forces the bell crank lever 28, 49, to swing in an anti-clockwise direction as viewed in Fig. 3 and causes the slasher lever actuating rod 46 to move toward the right. Motion of the slasher lever actuating rod 46 toward the right is transmitted through the cross connecting lever 47 to the intermediate lever releasing rod 45, causing the rod 45 to move toward the left simultaneously with the movement of the rod 46 toward the right. The movement of the intermediate lever releasing rod 45 toward the left causes the inclined surfaces 54 thereof to successively coat with the adjacent projections 42 on the intermediate levers 16 and to swing these levers a sufficient amount to release the lock afforded by the corresponding springs 51. This release of the intermediate levers 16 immediately permits the unbalanced pressure on the valves 95 corresponding to these levers to become effective and to successively place the valves into saws up position. The movement of the intermediate saw valves 95 into saws up position causes the intermediate levers 16 to take corresponding positions, as above explained, and places the intermediate saws out of cutting position. During the movement of the slasher lever actuating rod 46 toward the right, the inclined surfaces 55 successively coat with the adjacent projections 43 of the slasher levers 15 and gradually move these levers into positions corresponding to saws down position. As the slasher levers are swung into saws down position, the corresponding springs 51 automatically become effective to lock these levers into such position. It should be noted that during movement of the master lever 17 for actuation of the saws selectively, the intermediate saws which are at the time in saws up position as well as the slasher saws, which are in saws down position, will not be affected. Upon release of the master actuating lever 17 by the operator, the spring 41 again becomes effective in returning the master lever to normal or mid position, as above explained. The valve 25, piston 34 and rods 45, 46, thereupon automatically

move to normal or mid position, thus placing the mechanism in condition for either and immediate collective, selective or individual actuation of the saws.

The use of the motor to collectively and selectively actuate the individual levers reduces the amount of manual power necessary to operate the levers, to a minimum. The rapid successive actuation of the saws as above explained, either collectively or selectively, insures the provision of a proper supply of actuating fluid to the various actuating cylinders. The use of an unbalanced fluid pressure actuated valve for automatically returning the individual levers to saws up position provides a simple means of raising the saws after the individual levers are released from the lock afforded by the springs 51, and also permits the use of but a single connection between each individual lever and its valve.

By forming the portion of the connector 75 which passes over the guiding pulley 85 of a highly flexible connecting material, the use of a very small guiding pulley adjacent to the valve is permitted. It has been found that by guiding a piano wire such as it is desirable to use in this type of equipment, over a pulley of very small diameter, the small radius of the bend in the wire and the constant shifting of the bent portion over the pulley, causes the wires to break. With the use of chain or similar connector at the point of coaction of the operating connection with the pulley 85, this undesirable breaking of the connector is eliminated. The provision of a pivot 99 for the bracket 98 having its axis substantially in line with the valve 95, in conjunction with the use of a bell crank 74, pivoted upon the bracket 79 having its pivot 97 substantially in line with the connection 50, permits location of the saw actuating cylinders at any desired angle relative to the central point of control. It should also be noted that the various elements of the equipment herein disclosed are made interchangeable so far as possible in order to reduce cost of manufacture as well as to facilitate furnishing of repair parts.

It should be understood that it is not desired to be limited to the exact details of construction shown and described, for obvious modifications will occur to a person skilled in the art.

It is claimed and desired to secure by Letters Patent,

1. In combination with a table, a plurality of saws movable into and out of cutting position relative to said table, and means for effecting successive setting of said saws.
2. In combination with a table, a plurality of saws movable into and out of cutting position relative to said table, and means for effecting successive setting of said saws into either of said two positions.

3. In combination with a table, a plurality of saws movable into and out of cutting position relative to said table, individual means for normally setting each of said saws into either of said two positions, and means for effecting successive setting of said saws. 65
4. In combination with a table, a plurality of saws movable into and out of cutting position relative to said table, individual means for normally setting each of said saws into either of said two positions, and means for effecting successive setting of said saws into either of said two positions. 70
- 15 5. In combination with a table, a plurality of saws movable into and out of cutting position relative to said table, individual means for normally setting each of said saws into either of said two positions, and means for effecting either successive collective or successive selective setting of said saws. 75
- 20 6. In combination with a table, a plurality of saws movable into and out of cutting position relative to said table, individual means for normally setting each of said saws into either of said two positions, and means for effecting either successive collective setting of all of said saws out of cutting position, or successive selective setting of said saws into either of said two positions. 80
- 25 7. In combination with a table, a plurality of saws movable into and out of cutting position relative to said table, and a master lever for effecting rapid successive setting of said saws. 85
- 30 8. In combination with a table, a plurality of saws movable into and out of cutting position relative to said table, individual levers for normally setting each of said saws into either of said two positions, and a master lever for effecting successive setting of said saws. 90
- 45 9. In combination with a table, a plurality of saws movable into and out of cutting position relative to said table, fluid pressure actuated means for moving said saws into one of said two positions, controlling means for said fluid pressure actuated means, and a second fluid pressure actuated means tending to maintain said first mentioned fluid pressure actuated means in a position corresponding to out of cutting position of 100 said saws. 105
- 50 10. In combination with a table, a saw movable into and out of cutting position relative to said table, fluid pressure actuated means for moving said saw into one of said two positions, a valve for controlling said fluid pressure actuated means, means for actuating said valve, and means for es- 110
- 55 tablishing unbalanced fluid pressures on said valve tending to maintain said valve open to pressure. 115
- 60 11. In combination with a table, a saw movable into and out of cutting position relative to said table, fluid pressure actuated means for moving said saw into one of said two positions, controlling means for said fluid pressure actuated means, actuating means for said controlling means, a single flexible connection for communicating motion from said actuating means to said controlling means, and fluid pressure actuated means for moving said controlling means to a position to which corresponds out of cutting position of said saw when the end of said flexible connection adjacent to said actuating means is moved toward said controlling means. 120
- 65 12. In combination with a table, a saw movable into and out of cutting position relative to said table, fluid pressure actuated means for moving said saw into one of said two positions, controlling means for said fluid pressure actuated means, actuating means for said controlling means, and a single flexible connection for communicating motion from said actuating to said controlling means, said controlling means being movable by fluid pressure for maintaining said flexible connection taut. 125
- 70 13. In combination with a table, a saw movable into and out of cutting position relative to said table, fluid pressure actuated means for moving said saw into one of said two positions, controlling means for said fluid pressure actuated means, actuating means for said controlling means, a connection for communicating motion from said actuating to said controlling means, and fluid pressure actuated means for maintaining said connection taut at all times. 130
- 75 14. In combination with a table, a saw movable into and out of cutting position relative to said table, fluid pressure actuated means for moving said saw into one of said two positions, controlling means for said fluid pressure actuated means, fluid pressure actuated means tending to maintain said controlling means in a position to which corresponds out of cutting position of said saw, actuating means for said controlling means, and a single flexible connection for communicating motion from said actuating to said controlling means. 135
- 80 In testimony whereof, the signature of the inventor is affixed hereto in the presence of two witnesses.
- WILLIAM H. LIEBER.
- Witnesses:
- H. C. CASE,
ROB. E. STOLL.
